UNITED STATES PATENT OFFICE.

HERMIT E. GREGG, OF PORTLAND, OREGON, TO WHOM IT MAY CONCERN:
Improvement in Shoulder Straps for Trouser Suspenders.

1,221,722.

Specification of Letters Patent.

Patented Apr. 3, 1917.

Application filed January 14, 1916. Serial No. 72,094.

To all whom it may concern:

Be it known that I, HERMIT E. GREGG, a citizen of the United States, residing at Portland, in the county of Multnomah and State of Oregon, have invented certain new and useful Improvements in Suspenders; and I do hereby declare the following to be a full, clear, and exact description of the invention, such as will enable others skilled 10 in the art to which it appertains to make and use the same:

The invention relates to novel means adapted to be associated with a pair of suspenders for increasing the elasticity or resiliency of the suspenders and also admitting of the suspenders being attached to the waistband of a pair of trousers without necessitating the employment of buttons, and one object of the invention is to provide a 20 device of this nature, that can be manufactured cheaply, will be durable and efficient in operation and can be conveniently and expeditiously attached to the trousers.

Other objects will appear and be better understood from that embodiment of my invention of which the following is a specification, reference being had to the accompanying drawings forming a part thereof, 30 in which:

Figure 1 is a sectional detail view of the waistband of a pair of trousers, and the forward end of one of the shoulder straps of the suspenders and showing the connecting device attached thereto,

Fig. 2 is a side elevation of the device shown in Fig. 1,

Fig. 3 is a detail sectional view, taken through one of the attaching pads,

Fig. 4 is an interior view of one of the jaws of which the pad is formed,

Fig. 5 is a detail section of the rear ends of the shoulder straps, and showing the connecting device applied thereto,

Fig. 6 is a vertical sectional detail view, taken on the line $x-x$ of Fig. 5,

Fig. 7 is a detail view of one end of one of the shoulder straps with the connecting device removed therefrom,

Fig. 8 is a vertical detail sectional view, taken on the line $y-y$ of Fig. 5, and

Fig. 9 is a vertical sectional view, taken through the waistband of a pair of trousers and through one of the eyelets therein.

Referring to the drawing more in detail, the numeral 1 designates the shoulder strap

of a pair of suspenders each having its front and rear ends provided with the terminal loops 2, each loop having a depending portion 3 in which is formed a keyhole slot 4, 60 which is adapted to pivotally receive the headed stud 5 carried by a guide portion 6.

The guides 6 have rings 7 passed therethrough and substantially elliptical shaped links 8 are carried by the rings 7, the links 65 on the rings on the front ends of the shoulder straps being arranged in pairs.

A plurality of resilient connecting members are carried by the ends of the shoulder straps 1, and the connecting members located 70 at the front ends of the shoulder straps are arranged in pairs, and each of the connecting members includes a retractile spring 9, the upper end of which has connection to one of the links 8 on the adjacent ring 7. 75 The lower ends of the springs carry elliptical shaped links 11, which links in turn carry rings 12.

The rings 12 on the lower links 11 have a plurality of tabs 13 removably connected 80 thereto. Each tab 13 is formed of a leather strap, which is passed through the adjacent ring 12 and bent to provide the jaws 14 and 15. The lower or free end of the jaw 14 has its terminal bent inwardly, as shown at 85 16, and a metallic strip 17 has one end inserted between the terminal 16 and the inner side of the jaw 14 and secured thereto in any suitable manner, and the opposite end of the metallic strip extends upwardly and 90 across the point of juncture between the jaws 14 and 15 and then terminally extended downwardly to provide the curved bearing surface 18, for the adjacent ring 12, so as to prevent wearing of the strap. 95

A stud 19 is carried by the jaw 14 and has its shank extending through alined openings in the jaw 14 and the adjacent end of the metallic strip 17 and the inner bent terminal 16, and has its outer end provided with the 100 enlarged plate 20, which engages against the outer side of the jaw 14 and has its inner end provided with a head 21. The jaw 15 is provided with a socket 22, adapted, when the jaws are moved in the direction of each 105 other, to receive the head 21 on the inner end of the stud 19 and hold the jaws in operative position.

A trouser waistband is shown at 23 in Figs. 1, 2 and 9 of the drawings, and the 110 said waistband is provided at spaced points with eyelets 24. The eyelets 24 take the

place of the usual buttons, and when it is desired to attach the suspenders to the trousers, the jaws 14 and 15 are positioned on opposite sides of the waistband 23 and the shank of the stud 19 inserted through the eyelet 24 in the waistband, and the head 21 on the shank of the stud inserted into the socket 22 so as to secure the suspenders to the trousers!

10. What I claim is:

1. In suspender construction, the combination with the ends of the shoulder straps having pivoted guides thereon, of rings carried by the guides, substantially elliptical shaped links carried by the rings, and resilient connecting devices carried by the links.

2. A connecting device of the class described comprising a vertically disposed and contractile spring, a substantially elliptical shaped link carried by the lower end of the spring, a ring carried by the link, a strap extending through the ring and having its ends extended to provide jaws, a stud carried by one of the jaws and a socket carried by the other jaw for receiving the stud and the first-mentioned jaw when the jaws are locked in position.

In testimony whereof I affix my signature in presence of two witnesses.

HERMIT E. GREGG.
